PROOF PRESS

James Edgar Lee and Freeman Barney, Grand Haven, Mich., assignors to The Challenge Machinery Company, Grand Haven, Mich., a corporation of Michigan

Application October 26, 1936, Serial No. 107,660

5 Claims. (Cl. 101—285)

This invention relates to a proof press which is useful in printing proofs without the need of entering and locking the forms in a regular printing press. With our present invention the type, illustration plates and the like are properly held and located upon a movable bed associated with which is a pressure cylinder over which the paper to be pressed upon the inked type is carried. The paper in the movements of the cylinder and bed is pressed by the cylinder against the type which has been inked whereby a proof sheet is printed which may be examined for mistakes and correction thereof before the form is locked in a printing press for printing an indefinite number of copies, as in a newspaper or the like.

The present invention is concerned with many novel constructions and combinations for effectively attaining the various purposes of the invention. Among such purposes is a novel means for releasably clamping the edge of the paper to be printed, prior to the rotative movement of the cylinder and the longitudinal movement of the bed, both the clamping of the paper and the rotation of the cylinder thereafter, together with the movement of the bed, being performed by manually turning a crank attached to a shaft on which the cylinder is mounted. A further object and purpose of the invention is to provide a means for automatically elevating the cylinder at the end of a printing operation so that the printed proof sheet may be readily removed. Associated with the mechanism for elevating the cylinder is a manual means for accomplishing the cylinder elevation in the case of printing short proof sheets, the printing of which would be accomplished before the automatic cylinder elevation stage of operation is reached.

Further objects are to provide suitable stops for stopping the parts in predetermined position both the initial position of the mechanism and the final position after the proof sheet has been printed, and a novel means for securing a suitable tympan to the cylinder in a position such that the paper upon which the printing is pressed rides over the tympan and does not bear directly against a hard unyielding metallic surface such as the cylinder surface during the printing operation.

All of these objects and purposes and a great many others not at this time specifically stated will be apparent, as an understanding of the structures embodying the inventions is had from the following description, taken in connection with the accompanying drawings, in which,

Fig. 1 is a side elevation of the proof press made in accordance with our invention.

Fig. 2 is a fragmentary vertical section taken substantially on the plane of the broken line 2—2 of Fig. 3.

Fig. 3 is a transverse vertical section substantially on the plane of the broken line 3—3 of Fig. 2.

Fig. 4 is a fragmentary enlarged transverse section through the upper part of the cylinder 10 when the same is in its initial or starting position, and

Fig. 5 is a fragmentary transverse section substantially on the plane of line 5—5 of Fig. 4.

Like reference characters refer to like parts in the different figures of the drawings.

The machine which we have produced includes in its structure a horizontal supporting table 1 at the side edges of which are longitudinal upwardly extending sides 2. This table is supported at its corners by suitable posts 3. The upper edges of the sides 2 provide tracks for lengths of roller chain 4, as shown in Fig. 3. On the chains, which furnish an anti-friction support therefor, a bed 5 is mounted for longitudinal movement, having downwardly extending flanges or sides 6 which bear against the upper sides of the rollers of the chains 4. The type, held in a suitable chase, is placed upon and secured at the upper side of the bed 5 as indicated in dotted lines at 7 in Fig. 3. A longitudinal bar 8 is bolted to one side of the bed 5 and its upper edge is provided with a plurality of consecutive gear teeth thus making a rack, as best shown in Fig. 1.

Two housing members 9 are secured, one at each side of the machine, being permanently bolted at their lower portions to the sides 2 of the table previously described and extending upwardly therefrom. The housing members are formed with elongated vertical openings in each of which a journal box 10 is slidably mounted, having connection at its lower side to the upper end of a post 11. A screw threaded rod 12 threads into the lower end of the post and passes downwardly through a cross bar 9a extending between the parts of the housing member at each side of the vertical opening described. At its lower end the rod 12 threads into a vertical cylindrical member 13 integral with which, at its lower end, is an eccentric housing 14. Eccentrics 15 are mounted in the housings 14, a horizontal shaft 16 extending across and underneath the table and being keyed to the eccentrics off-center thereof as shown in Fig. 1. The shaft is

5 mounted in suitable bearings 16a (Fig. 3) fixed to the underside of the table 1. It is evident that on turning the shaft 16 the journal boxes 11 will be elevated. A coiled spring 17 is disposed around each of the threaded rods 12, these springs resting at their lower ends on the cross members 9a, and the tension of the springs is adjusted by means of nuts 18 threaded on the members 12 against the upper ends of the 10 springs, whereby the springs serve to partly balance the weight which is carried by the journals 10. A gear 19 is fixed to the shaft 16 substantially midway between its ends and is located in a position to mesh with the rack teeth cut at 15 the underside of a bar 20 which is slidably mounted at the upper side of the table 1 (Fig. 2), the rack operating the gear 19 at the ends of the inward and outward movements of the bed 5.

10 A shaft 21 extends between and is rotatably mounted at its ends in the journals 10 on which the pressure cylinder 22 is loosely mounted. At one end of the cylinder 22 a gear 23 is secured (Fig. 3) which is in meshing engagement with the rack at the upper side of the bar 8. A crank 24 is secured to one end of the shaft 21 to manually turn the shaft.

15 At the end of the cylinder 22, opposite where the gear 23 is located, a driving and cam member 25 is keyed having a circular opening 26 therein (Fig. 2). A pin 27 of less diameter than the diameter of the opening 26 projects from the end of the cylinder 22 into said opening. On turning the shaft counterclockwise (Fig. 2) the first movement is to swing the driving member 25 to the right and there will be no turning movement of the cylinder until the opposite side of the opening 26 engages against the pin 27.

20 From the upper portion of the member 25, in the position in which it occupies at the initial or starting position of the mechanism (shown in Fig. 2), a cam finger 28 extends to one side of which is a dwell 29 located inwardly toward the axis of the shaft 21 from the outer end of the cam finger 28. A lever 30 is pivotally mounted 25 between its ends on one end of a rock shaft 31 which extends lengthwise of and within the outer curved limits of the cylinder 22 and is mounted for rocking movement in the ends of the cylinder. One arm of the lever 30 carries a 30 roller 32 which, in the position of the parts shown in Fig. 2, bears against the outer end of the cam finger 28. It is apparent that with the first turning movement of the shaft 21 and before any rotation of the cylinder 22 takes place 35 the cam finger 28 will have moved counterclockwise to the left away from the roller 32 which will then bear upon the dwell 29 and the rock shaft 31 will be rocked clockwise a short distance. The rocking is performed by a coiled spring 35. 40 A rod 33 is pivotally connected to the opposite end of the lever 30 and extends slidably through a block 34 swivelly connected at the same end of the cylinder 22, the coiled compression spring 35 being located around the rod between said 45 block and the head of said rod, the force of the spring tending to move the lever 30 in a counterclockwise direction.

45 The cylinder 22 has a continuous cylindrical surface around the major portion thereof but 50 such cylinder is cut away for a part of its area and a clamping flange 36 turned inwardly as shown in Fig. 4 substantially at the uppermost part of the cylinder when said cylinder is in its initial position. A clamping bar 37 is located 55 alongside of the clamping flange 36 and suitable

clamping screws 38 are passed through the bar 37 and threaded into the flange 36. Pins 39 having rounded heads are carried by the flange 36 below the clamping screws 38 so that when the screws are tightened the upper portions of 5 the clamping bar 37 are brought into tight clamping engagement against an inturned edge portion of a tympan 40. The tympan may be and usually is of suitable paper which is carried around substantially three-fourths of the 10 surface of the cylinder, the opposite end being rolled upon a suitable roll-up, not shown in the drawings. It is evident that whenever any tympan section has become deteriorated or damaged in use, it may be cut from the roll of paper to which 15 attached and additional paper then unrolled and clamped between the flange 36 and the clamping bar 37.

20 At the upper part of the clamping bar 37 a plurality of vertically spaced apart stop fingers 41 are permanently secured and extend a short distance above the upper edge of the bar 37. On the rock shaft 31 a plurality of clamping fingers 42 (Figs. 3 and 4) are mounted and extend so that their free ends come above the bar 37 and 25 between the stop fingers 41. When the shaft 31 is automatically rocked at the first part of the turning movement given to the shaft 21, that is, when the roller 32 drops to the dwell 29, the free end of the clamping fingers 42 come down 30 against the upper edge of the clamping bar 37, or in practice, against the edge of paper which is to be printed and which has been inserted so that its edge comes against the stop fingers 41, being thereafter clamped by the spring pressure 35 of spring 35 acting through the clamping fingers 42. The paper is fed to position over an inclined feed table. Supporting members 43 are fixed at 40 their lower portions to the table 1 and the inclined feeding table 44 is pivotally connected at 45 to the supports 43 occupying the position shown in Fig. 1 when in use, though the table may be turned about the pivots 45 to an out-of-the-way position.

45 Bent arms 46 are secured to a rod 47 which is mounted at its ends on brackets 48 attached to the upper part of the housings 9. The bent arms 46 extend over the cylinder 22 and have a shaft 51 rotatably mounted between and at their free ends on which are rollers 49 which ride upon the 50 ends of the cylinder 22. A plurality of downwardly curved members 50 are located on and attached to the shaft 51. From the shaft 47 a plurality of spaced members 52 extend downwardly, to each of which a curved spring bar 53 55 is secured extending downwardly and partly around the cylinder 22 (see Fig. 2).

60 Brackets 54 and 55, located in different vertical planes, are bolted to the upper side of the table 2 (Figs. 2 and 3) each of which at its upper end carries a rod 56 around which is a coiled bumper spring 57, each rod 56 at its end having a nut with a washer 58 between the adjacent end of the spring 57 and the nut (Fig. 2). Brackets 59 and 60 also located in different vertical planes are permanently secured substantially at the opposite ends of the bar 20. Two 65 cooperating members 61 and two stops 62, one only of each being shown in Fig. 2, are connected to the underside of the bed 5. When one 70 of the members 61 engages bracket 60 it moves the bar 20 longitudinally, thereby automatically rotating the shaft 16 and lifting the cylinder. This occurs before one of the stops 62 comes against the corresponding spring bumper 75

stop 57 which thereupon prevents further movement of the bed 5. The other member 59 and the other spring bumper stop 58 carried by the bracket 54, when engaged by cooperating members like those shown at 61 and 62 secured adjacent the opposite end of the bed 5, reverses the movement of the bar 20, lowering the cylinder to initial position, after which the bed 5 is stopped in the initial position which it had before a printing operation took place.

The shaft 16 is supplied with a crank 63 for manually lifting the cylinder 22 to an upper position in certain instances where the length of the proof sheet is shorter than its usual or maximum length, and the operator does not need to rotate the cylinder the full distance and move the bed 5 the full distance to automatically elevate the cylinder.

In operation, with the structure described, the parts being in the position shown in Fig. 2, a sheet of paper, upon which a proof is to be printed, is slid down the feed table 44 until its end edge strikes against the stop fingers 41. When this occurs the clamping fingers 42 are elevated above the position shown in Fig. 4 and the end edge of the paper may pass underneath the free ends of the clamping fingers 42. The operator thereupon grasps the crank 24 and manually turns the shaft 21. At the beginning of the movement, or while the pin 27 is moving relatively from one side to the other of the opening 26, roller 32 rides down to the dwell at 29, the shaft 31 is rocked and the fingers 42 clamp upon the edge of the paper. With a continued rotation of the shaft 21 in a counterclockwise direction (referring to Fig. 2) the paper is drawn underneath the rollers 49 and underneath the spring members 53, and at the same time, due to the engagement of the gear 23 with the rack on the bar 8, the bed 5 is moved inwardly from the position shown in Fig. 1 underneath the cylinder, riding upon the rollers of the chains 4. The type indicated in dotted lines at 7 having been suitably inked, an impression of the type upon the paper occurs.

During the last part of the movement of the bed 5 one of the stops 61 comes into contact engagement with the bracket 60 moving the bar 20 longitudinally and rotating the shaft 16 with a consequent lifting of the cylinder above the paper which has been printed so that the printed proof sheet may be readily removed. One of the stops 62 described thereafter strikes against the spring bumper carried by the bracket support 55 limiting the inward movement of the bed and stopping the machine.

When the operator returns the parts to the initial position by reversing the turning movement of the shaft 21 the first effect of such turning movement is to move the cam member 25 to the position shown in Fig. 2, whereupon the cam finger 28 rides underneath the roller 32 with a consequent lifting of the clamping fingers 42 to release the paper from the cylinder 22 so that it may be readily removed. And as previously stated, the stop 62 will strike against the spring bumper stop carried by the bracket 54 to properly stop the parts at their initial position, the bar 20 having previously been moved back by the engagement of the parts 59 and 61 so as to lower the cylinder, but leaving the clamping fingers in an upper inoperative position.

In the case of printing proof on short sheets, so that the full inward movement of the bed 5 need not take place, lifting of the cylinder 22

is by manually operating the crank 63. The return of the parts to the initial position will result in an automatic lowering of the cylinder the same as though the inward transverse movement of the bed had been to its innermost position instead of part way.

The structure described has proven very practical and satisfactory. There is no pressure of the clamping fingers against the tympan covering of the cylinder or any possibility of the clamping fingers pressing the paper into the tympan with a resultant wrinkling of the paper at each side of the depressions. The construction is very efficient, is durable, and of a long life and has proved particularly satisfactory in use. The invention is defined in the appended claims and is to be considered comprehensive of all forms of structure coming within their scope.

We claim:

1. In a structure of the class described, a horizontal support, a type carrying bed mounted for longitudinal movement on the support, a cylinder carried on said support above the bed, means for manually turning the cylinder, gearing between the cylinder and bed for moving the bed longitudinally on turning said cylinder, a shaft on which the cylinder is mounted, bearings for the shaft, vertical supports in which said bearings are vertically adjustably mounted, a second shaft carried by the horizontal support, eccentricities thereon, means in journals on said vertical supports between said bearings and eccentricities whereby turning said second shaft moves said bearings for the first shaft vertically to raise or lower the cylinder with respect to the bed, springs on said last named means to partly balance the weight carried by said journals, and means to regulate the tension of said springs.

2. A construction containing the elements in combination defined in claim 1, combined with a rack carried by the support and a gear on said second shaft, said rack engaging with the gear at a predetermined position of the bed to thereby automatically elevate said bearings and the cylinder on continued movement of the bed.

3. In a printing press, a support, a bed longitudinally movable over said support, a manually operable rotatable cylinder adapted to be turned in either direction, gearing between the cylinder and bed for longitudinally moving the bed on turning the cylinder, a shaft carrying said cylinder, means for adjustably supporting said shaft whereby the same may be adjusted in a vertical direction to raise or lower the cylinder, and means for automatically elevating said cylinder at the substantial completion of a movement of the bed in one direction and for lowering the cylinder to its initial position on substantial completion of a movement of the bed in the opposite direction, including a second horizontal shaft mounted below said first shaft, journals on said first shaft, means connecting said journals with eccentricities on said second shaft and a coiled spring on said last named means for balancing the weight carried by said journals, and means for adjusting the tension of said springs.

4. In a printing press, a support, a bed longitudinally movable back and forth thereon, a cylinder mounted for rotation above the bed, gearing between the cylinder and bed for longitudinally moving the bed on rotation of the cylinder, manually operable means for turning said cylinder, a shaft on which the cylinder is mounted, vertically adjustable journal boxes carrying the ends of the shaft, a second shaft

mounted on the support, connections between said second shaft and the journal boxes whereby rotation of said second shaft in one direction lifts said journal boxes and in the opposite direction lowers the same, a rack bar carried by the support, a pinion on said second shaft, said rack bar being moved by the bed to engage with the pinion substantially at the ends of the movements of the bed in opposite directions to thereby rotate the shaft in one direction when the bed has been moved substantially to its extreme of movement in one direction and rotating said second shaft in the opposite direction when the bed has been moved to substantially its ex-

treme of movement in the opposite direction, coiled springs on the connections between said second shaft and the journal boxes to balance the weight carried by said journal boxes, and means to regulate the tension of said springs. 5

5. A construction containing the elements in combination defined in claim 4, said rack being slidably mounted on the support and cooperating means on the rack and bed for moving and stopping said rack bar at predetermined positions on the support in both directions of movement of the bed. 10
